UNITED STATES PATENT OFFICE.

GEORGE FLEMING, OF PRINCETON, TEXAS.

ELECTRICALLY-HEATED BOILER.

1,322,556.

Specification of Letters Patent. Patented Nov. 25, 1919.

Application filed January 29, 1919. Serial No. 273,776.

To all whom it may concern:

Be it known that I, GEORGE FLEMING, a citizen of the United States, residing at Princeton, in the county of Collin and State of Texas, have invented certain new and useful Improvements in Electrically-Heated Boilers, of which the following is a specification.

The invention relates to boilers and more particularly to means whereby the same is electrically heated, the purpose being to provide a compact structure which occupies a minimum amount of space and is effective and reliable in operation.

The invention is adapted for use in connection with various types of boilers for heating water for generating steam, the electric heater being comparatively small and arranged within the water space of the boiler and surrounded by the water, thereby being enabled to quickly heat the water for any desired purpose.

The drawing illustrates a preferred embodiment of the invention. However, it is to be understood that in adapting the same to meet different conditions, various changes in the form, proportion, and minor details of construction may be resorted to without departing from the nature of the invention as claimed hereinafter.

Referring to the drawing hereto attached, Figure 1 is a vertical longitudinal section of a boiler provided with an electric heater embodying the invention.

Fig. 2 is a transverse section on the line 2-2 of Fig. 1 looking to the right as designated by the arrow.

Corresponding and like parts are referred to in the following description and indicated in both views of the drawing by like reference characters.

The boiler 1 may be of any design or capacity and is provided at one end with an opening which is closed by means of a plate 2, whereby access may be readily had to the interior of the boiler for any desired purpose. The boiler is shown provided with a steam space 3 from which the steam may be taken for driving an engine or for other purposes.

The electric heater is located within the water space of the boiler and is mounted upon pillows 4 which may be of any insulating material to prevent loss of current.

The heater comprises a shell or casing 5 which may be of any size or construction. As indicated, the casing 5 is of cylindrical form and is disposed horizontally within the boiler. A plate 6 closes the open end of the casing, thereby providing for access to the interior of the casing for any purpose. A tube 7 projects axially from the plate 6 and passes through an end wall of the boiler and is electrically insulated therefrom. A plurality of fittings 8 serve to insulate the tube 7 from the end of the boiler and also to insure the formation of a water-tight joint. A wire 9 passes through the tube 7 and is adapted to be connected with any suitable source of supply of electricity. The tube 7 is filled with insulating material to prevent contact of the wire 9 therewith and also to insure a close joint. A wire 10 is electrically connected with the tube 7 and is adapted to be connected with the other terminal or pole of the source of electric supply.

The electric heating means is located within the casing 5 and may be of any well known form. In accordance with the present invention it is preferred to provide a plurality of rings 11 which are connected by means of arms 12 with hubs 13. The arms 12 and hubs 13 may be of any insulating material, whereas the rings 11 are preferably of metal and are provided at their sides with projections 14 which are in contact when the heating elements are in position. A shaft 15 is disposed centrally within the casing 5 and is supported at its ends in the end walls or heads of the casing. The heating elements are strung upon the shaft 15 and the latter is of non-circular form in cross section so as to maintain the heating elements in given relative positions, the hubs of the heating elements being provided with openings to snugly receive the shaft 15 and thereby prevent any relative turning of the heating elements upon the shaft. The electric heater is supported intermediate its ends by a bed 16 of insulating material, said bed being in the form of a strip. One of the terminal rings is electrically connected with the wire 9, whereas the other terminal ring is electrically connected with the casing 5, as indicated at 17. In this manner the circuit entering by way of the wire 9 passes through the series of rings and enters the

casing 5 and passes through said casing and tube 7 to the wire 10, thereby completing the circuit.

As indicated the electric heater is disposed within the water space of the boiler and when the circuit is closed the heating elements generate heat which heats the walls of the casing and the latter in turn radiates the heat and raises the temperature of the water in which the heater is immersed. The heat may be regulated by means of an air tube 18 which extends through a side of the boiler and a side of the casing 5. Fittings 19 maintain a close joint between the tube 18 and the boiler. A suitable valve 20 is provided in the length of the tube 18 to regulate the admission of air into the casing 5 for moderating the temperature of the electric heater as occasion may require.

The foregoing description and the drawing have reference to what may be considered the preferred, or approved, form of my

invention. It is to be understood that I may make such changes in construction and arrangement and combination of parts, materials, dimensions, et cetera, as may prove expedient and fall within the scope of the appended claim.

Having thus fully described my invention, what I claim as new and desire to secure by Letters Patent is:—

An electric heater of the character specified, comprising a casing, a shaft within the casing, insulating elements mounted upon the shaft and electrically heated rings supported by the said insulating elements and provided at their sides with projections which are in contact.

In testimony whereof I affix my signature in presence of two witnesses.

GEORGE FLEMING.
